UNITED STATES PATENT OFFICE.

WILLIAM S. MENDEN, OF BROOKLYN, NEW YORK.

DOOR OPERATING AND CONTROL DEVICE

1,094,804.

Specification of Letters Patent. Patented Apr. 28, 1914.

Original application filed January 2, 1913, Serial No. 739,755. Divided and this application filed April 30, 1913, Serial No. 764,589.

To all whom it may concern:

Be it known that I, WILLIAM S. MENDEN, a citizen of the United States, residing in the borough of Brooklyn, county of Kings, 5 and State of New York, have invented certain new and useful Improvements in Door Operating and Control Devices, of which the following is a full and clear specification.

10 This invention forms a division of my pending application Serial No. 739,755 and relates to means for automatically opening and closing the doors of passenger cars and the like, and has for its primary object to 15 provide an improved device of this character which will prevent the door of a car being opened while it is in motion but which is automatically brought under the control of the conductor as soon as the car comes to 20 rest and remains under his control as long as the car is at rest.

Another object is to provide suitable and efficient means whereby when the conductor's hands are fully occupied with taking 25 fares and with other duties, he can control the door-operating mechanism with his feet.

Other and further objects will appear in the specification and be pointed out in the appended claims, reference being had to the 30 accompanying drawings in which,—

Figure 1 is a fragmentary horizontal section of the central portion of a car in the preferred embodiment of my invention, showing a plan of the center platform 35 ret and railings; Fig. 2 is an elevation of the pedestal and turret; Fig. 3 is a section on the line III—III, Fig. 2; Fig. 4 is a fragmentary detail section of the lower portion of the pedestal and turret, parts being 40 broken away and parts shown in elevation; Fig. 5 is a fragmentary detail section of parts of the pedestal and turret showing the interlocking device; Fig. 6 is a diagram of the wiring connections; Fig. 7 is a section 45 on the line VII—VII, Fig. 2; Fig. 8 is a vertical section of the pedestal and turret housing; Fig. 9 is an enlarged fragmentary section of the upper end of pedestal and housing showing operating connections between the brake-operating shaft and the operating lever on the outer wall of said turret or housing, parts being broken away and parts shown in elevation; and Fig. 10 is a fragmentary side elevation of the same.

55 Referring more particularly to the draw-

ings and to the embodiment shown therein in which the conductor is located upon a central platform 1, provided with suitable barricades or railings 2 which form a central entering passageway 3 and spaced exit 60 passageways 4 leading from opposite ends of the car, said barriers or railings being reversible from one side to the other of said platform as indicated in dotted lines. Centrally disposed with respect to said platform, is a pedestal or turret 5, which divides the entering passengers into two columns as indicated by the arrows in Fig. 1, going toward the opposite ends of the car. The preferred construction of the pedestal or turret 65 will be understood from Figs. 2 to 5 inclusive. Thus the flanged base plate 6 is rigidly secured to the central platform, a central column or standard 7 being preferably integral with the flanged base 6. Mounted 70 on the upper end of said standard are a plurality of contact boxes 8 within which are arranged the terminals of a plurality of circuits for controlling the operation of the doors, signals, brakes, etc., as will appear 75 in the following description: Rotatably mounted upon the flange base 6 and concentrically disposed with respect to the standard 7, is the outer housing or turret 9 which serves to open up to the conductor 80 only those devices which control the car from the side on which he is standing. The turret is locked in either position by means of a latch 10 (see Fig. 5), pivoted at 11, said latch being normally retained in locking 85 position by means of a spring 12. The head of the latch 10 projects through an opening 13 in the outer wall of the turret, and the nose of said latch in locking position engages in a hole 14 in the standard 90 or pedestal 7. In the lower end of the pedestal 7 are arranged contact boxes 15, each of which are adapted to receive the spaced ends of conductors (not shown). A pin 16 when pressed inwardly, serves to 95 bridge the gap between said wires, another operation which serves to bring about the energization of a door moving circuit in the manner to be hereinafter pointed out. An operating lever 17 which is pivoted at 100 18 in a small bracket 19 mounted on the turret 9, is provided with a pedal 20 at its lower end. A plunger 21 having a pin 22 movably mounted in a slot 23 in the lever 17, is adapted to displace the pin 16 when the con- 11

ductor's foot is placed upon the pedal 20, enabling the conductor to close the doors when his hands are busily engaged with other matters connected with his duties. 5 The several contact boxes 8 are adapted to contain the ends of wires between which exist the gaps forming normally broken circuits, said circuits being suitably arranged to effect the door opening and closing movements and the energization of a signal for the motorman. Of course, arrangements can be made for any other circuits which it may be desired to operate from the conductor's position on the platform, the ones disclosed being sufficient to illustrate the broad idea in this connection. In Fig. 2, the push buttons 24, 25 and 26 are for controlling these circuits.

Referring now to Fig. 6, the controlling 20 circuits for the several mechanisms, will be understood. Leading from the positive line 27 is a wire 28 which is connected to a resistance coil 29 connected up to a controller 30, said controller being connected by a wire 31 with the solenoid 32 which is grounded at 33 in the negative line 34. The energization of the solenoid 32 serves to elevate the plunger 35 together with a switch lever 36, to which said plunger is connected, said lever 36 being pivoted at 37 to adapt it to close a circuit through a wire 38, switch 36, contact 39, wire 40, resistance 41, wire 42, armature 43 of the motor, field coil 44 and wire 45 which is grounded in the line 34. A 35 branch circuit is simultaneously energized by the closure of switch 36, said branch circuit including wire 46 which is connected to the wire 40 adjacent the coil 41, solenoid 47, wire 48, field winding 44 and wire 45 which is grounded in line 34. The function 40 of this circuit is to energize solenoid 47 when the circuit is closed by switch 36 and current supplied to the motor 43—44, the solenoid 47 being designed to maintain an armature 49 in elevated position with respect to a 45 pair of contacts 50 included in the door operating circuits to be presently referred to. In order to provide for the energization of the solenoid 47 at times when the current has been shut off from the motor 50 by the drop of switch 36 and while the car is still in motion, a lesser circuit is provided whereon the motor becomes a generator. Thus a laterally extending branch 51 is 55 connected to the wire 42 and a similar branch 52 is connected to the wire 48, said branches being provided with spaced contacts 53. Normally suspended above the contacts 53 and adapted to bridge the space therbetween, is an armature 54 provided with a stem or plunger 55 subject to the solenoid 56 which is wound upon the hollow core 57 within which the plunger 55 reciprocates. The energization of the solenoid 60 56 is normally maintained by current de-

rived from wire 31 by means of a branch wire 58 when the controller 30 is properly manipulated for this purpose. The solenoid 56 is connected to the wire 45 which is grounded in line 34. It will be apparent 70 therefore that as long as the motor is being provided with current through the switch 36, the solenoid 56 will also be supplied with the current necessary to maintain the armature 54 in raised position. On the other 75 hand, as soon as the current is cut off from the motor by deenergizing the solenoid 32, the solenoid 56 also becomes deenergized and the armature falling upon the contacts 53 closes the lesser circuit and serves to maintain 80 the energization of the solenoid 47 by current derived from the motor as a generator. Suitable and efficient means are provided for moving the door 59, by attaching thereto a rod 60. On the end of said 85 rod is a piston 61 adapted to reciprocate in the cylinder 62, said cylinder being connected by a pipe 63 to a valve housing 64, said housing being connected to an air reservoir 65 by means of a pipe 66. A second rod 90 67 is rigidly connected to the first rod 60 in the manner indicated in Fig. 6, and is provided with a piston 68 which is adapted to reciprocate in the cylinder 69. Said cylinder 69 is connected by pipe 70 with 95 the valve housing 64. Controlling the valve in the housing 64 is a lever arm 71 which is connected at its outer end with a plunger rod 72 which is adapted to be moved first in one direction and then the other by means 100 of solenoids 73 and 74. The solenoids 73 and 74 are grounded in the line 34 by the wire 75 which is common to both of them. A wire 76 connects the solenoid 73 with the press button 24 while a wire 77 leads from 105 the press button 25 to the solenoid 74. A wire 78 which is common to the press buttons 24 and 25, leads to the left hand contact 50, the right hand contact 50 being connected to the line wire 27 by means of a wire 110 79. The pedal 20 is diagrammatically represented in Fig. 6 as constituting a switch which is adapted to be depressed upon a contact 80, said contact being connected by a wire 81 to the wire 77 which leads from 115 the solenoid 74. A wire 82 which is connected to the pedal 20, joins the wire 78 at 83 so that when the armature 49 closes the gap between contacts 50, any of the following circuits may be closed. First, to open 120 the door 59, push button 24 is manipulated to close a circuit including wire 79, contacts 50, armature 49, wire 78, wire 76, solenoid 73 and wire 75, the solenoid 73 being energized to move the plunger 72 to the left, 125 thus admitting air or other fluid through the pipe 70 into the cylinder 69. Second, by pressing button 25, a circuit is completed through wire 79, contacts 50, armature 49, wire 78, wire 77, solenoid 74 and wire 75, a 130

circuit which energizes solenoid 74 and moves the plunger 72 to the right into the position shown on the drawing, thus releasing the air in cylinder 69 and admitting air to cylinder 62 to close the door 59. Or, in the event that the conductor's hands are busy, pedal 20 may be depressed upon contact 80, closing a circuit through wire 79, contacts 50, armature 49, wire 78, wire 82, pedal 20, wire 81, wire 77, solenoid 74 and wire 75, which effects the same result as the last described circuit, namely, closing the door.

The push button 26 serves in the present embodiment of my invention, to close a circuit including a lead wire 84, wire 85, signal 86 for signaling the motorman, and wire 87 which is grounded in line 34. When the door is in closed position as shown in Fig. 6, a pin 88 which is embodied in the stile 89 of the door 59, bridges the space between a pair of contacts 90 and serves to close a circuit including lead wire 91, wire 92, signal 93 (preferably visible), and wire 94 which is grounded in line 34. In order to provide suitable and efficient means for making it impossible to energize the motor and so start the car, while the door 59 is open, means for short-circuiting said motor is provided in the following manner: Within a spring housing 95 and surrounding a stem 96, is a spring 97 which is under compression between the end wall of said housing and a piston 98 on the stem 96. When the door is in closed position, pressure is transmitted from the spring 97 to an armature 99 through the stem 100, said armature being thereby adapted when the door 59 is open to move down onto a pair of spaced contacts 101, one of said contacts being connected by a wire 102 to the ground wire leading from solenoid 32. The other of said contacts 101 is connected by a wire 103 to the wire 31 leading from the controller 30. Hence, when the door is opened the following low resistance short-circuit is closed, namely, wire 28, controller 30, wire 31, wire 103, contacts 101, armature 99, wire 102 and wire grounded at 33 in line 34. This short circuit cuts out the solenoid 32 and makes it impossible to raise the switch 36 and hence, makes it impossible to energize the motor until the door is again closed and the armature 99 displaced from contacts 101.

Referring now to Figs. 7, 8, 9 and 10, journaled within the lateral walls of the pedestal 7 and adjacent the upper end of said pedestal, is a shaft 105. Keyed to this shaft is a lever arm 106 to which the upper end of a connecting rod 107 is pivotally connected. The lower end of the connecting rod 107 is connected to a lever 108 which serves to operate a suitable brake controlling apparatus which in the present embodiment includes a valve 109 in a conduit 110,

said conduit being preferably a pipe for connecting a reservoir for air (not shown) to the brake operating cylinder (not shown). As shown best in Figs. 8 and 9, each end of the shaft 105 is provided with a clutch element 111, which is adapted to receive a grooved head or clutch element 112, which is mounted upon a stub shaft 113 which is journaled in the wall of the turret 9. Depending from the stub shaft 113 is an operating handle 114 which carries a resiliently mounted pin 115 which is adapted to successively engage a plurality of notches 116 which are suitably spaced within a plate 117 which is mounted on the side wall of the turret 9. Whenever the handle 114 is raised into the position shown in dotted lines in Fig. 10, the shaft 105 will be rotated 90°, thus serving to permit a flow of air through the pipe 110 for operating the brakes. The resiliently mounted pin 115 is adapted to retain the handle 114 in raised position to sustain a full operation of the brakes in an emergency. By an inspection of Figs. 2 and 3, it will be apparent that the openings 118 in the lateral wall of the turret 9 are adapted to uncover the push buttons 24, 25 and 26 on opposite sides of the entrance platform, thus bringing the mechanisms controlled by said buttons, within the ready reach of the conductor stationed on either side of said platform.

What I claim is:

1. In a car, an entrance platform intermediately of the ends of said car, side doors for said platform, a revoluble turret in the center of said platform, door operating devices, and operating connections between said devices and said turret.

2. In a car, a platform disposed intermediately of the ends of said car, side doors for said platform, a revoluble turret at the center of said platform, door operating devices, operating connections therefor terminating in said turret, and guide rails arranged transversely of the platform to one side of said turret to form separate passageways for entering and leaving passengers.

3. In a car, a platform disposed intermediately of the ends of said car, side doors for said platform, a revoluble turret at the center of said platform, door operating devices, operating connections therefor terminating in said turret, and guide rails arranged transversely of the platform to one side of said turret to form separate passageways for entering and leaving passengers, said guide rails being suitably mounted to be swung from adjacent one door into position adjacent the other door.

4. In a rapid transit car provided with an entrance platform, a door for said platform, a pedestal on said platform adapted to provide a conductor's station, and means for opening and closing said door, said

- means including a pedal lever mounted on said pedestal.
5. In a rapid transit car provided with an entrance platform, a door for said platform, a pedestal on said platform adapted to provide a conductor's station, and means for opening and closing said door, said means including a pedal lever mounted on said pedestal, and other devices on said pedestal adapted to be manipulated by hand.
6. In a car, the combination of a pedestal, an operating instrumentality mounted thereon, and a rotatable housing for said pedestal, said operating instrumentality being operable when said housing is in a predetermined position with respect to said pedestal.
7. In a passenger vehicle, the combination with an entrance platform, of a pedestal suitably disposed on said platform to provide a conductor's station, controlling instrumentalities carried by said pedestal, said controlling instrumentalities being provided in duplicates, presented toward opposite edges of said platform to permit the conductor to occupy either side of the platform.
8. In a passenger vehicle, the combination with an entrance platform, of a pedestal suitably disposed on said platform to provide a conductor's station, and controlling instrumentalities carried by said pedestal and a turret rotatable on said pedestal, said turret being provided with an aperture to permit access to said instrumentalities.
9. In a passenger vehicle, the combination with an entrance platform, of a pedestal mounted thereon, controlling instrumentalities mounted on opposite sides of said pedestal, and a turret housing said pedestal, said turret being rotatable around said pedestal and provided with an opening which is adapted to be brought into positions exposing said instrumentalities successively.
10. In a passenger vehicle, the combination with a pedestal, of a plurality of pairs of controlling instrumentalities carried by said pedestal, and a rotatable turret housing said pedestal, said turret being provided with openings for giving access to one instrumentality in each of said pairs for different positions of said turret.
11. In a passenger vehicle, the combination with a pedestal, of a plurality of pairs of controlling instrumentalities carried by said pedestal, and a rotatable turret housing said pedestal, said turret being provided with openings for giving access to one instrumentality in each of said pairs for different positions of said turret, and means for locking said turret in its different positions.
12. In a passenger vehicle provided with an entrance platform, the combination with a pedestal, of a plurality of controlling instrumentalities carried by said pedestal, and a turret rotatable about the axis of said pedestal, said turret being provided with an opening adapted to correspond to different instrumentalities in different positions of said turret.
13. In a passenger vehicle, provided with an entrance platform, the combination with a pedestal, of a plurality of controlling instrumentalities carried by said pedestal, and a turret rotatable about the axis of said pedestal, said turret being provided with an opening adapted to correspond to different instrumentalities in different positions of said turret, said turret being provided with suitable means for locking said turret against displacement in each of its positions.
14. In a car, provided with a platform, a pedestal mounted on said platform, a rotatable housing for said pedestal, and an operating instrumentality controlled by the relative position of said housing with respect to said pedestal.
15. In a car, provided with a platform, a pedestal mounted on said platform, a rotatable housing for said pedestal, and an operating instrumentality controlled by the relative position of said housing with respect to said pedestal, said operating instrumentality being mounted on said pedestal.
16. In a passenger car, the combination of a pedestal provided with suitable means for mounting the spaced ends of an operating circuit, a turret rotatable about the axis of said pedestal, and means carried by said turret for closing the space between said ends.
17. In a passenger car, the combination of a pedestal, a rotatable housing therefor, an operating instrumentality comprising cooperating parts mounted in said pedestal and housing respectively.
18. In a passenger car, the combination of a pedestal, a push button for controlling an operating circuit mounted on said pedestal, a housing for said pedestal, and a plunger reciprocably mounted in said housing to operate said push button.
19. In a passenger car, the combination of a pedestal, a push button for controlling an operating circuit, mounted on said pedestal, a housing for said pedestal, and a plunger reciprocably mounted in said housing to operate said push button, said plunger being provided with an operating pedal movably mounted on the outer wall of said housing.
20. In a passenger vehicle, the combination of a pedestal, a turret movable about the axis of said pedestal, a vehicle controlling instrumentality mounted on said pedestal, and means carried by the turret for operating said instrumentality in different positions of said turret.
21. In a car, provided with a platform, a pedestal mounted on said platform, a rotatable housing for said pedestal, and an operating instrumentality controlled by the relative position of said housing with respect to said pedestal.

tive position of said housing with respect to said pedestal, said operating instrumentality being mounted on said pedestal, and said housing having an opening movable into and out of position to make said instrumentality accessible.

22. In a passenger vehicle, the combination of a pedestal, a vehicle controlling instrumentality carried by said pedestal, and 10 operating means for said instrumentality movable about said pedestal and adapted to operate said instrumentality from different stations on said platform.

23. In a passenger vehicle, the combination of a pedestal, a rotatable turret for 15 housing said pedestal, a vehicle controlling instrumentality connected with said pedestal, and an operating instrumentality connected with said turret and adapted to operate said controlling instrumentality in different positions of said turret with respect to said pedestal. 20
